UNITED STATES PATENT OFFICE.

THOMAS AITKEN, OF CUPAR-FIFE, SCOTLAND.

METHOD OF FORMING SURFACES ON ROADS.

No. 918,490.

Specification of Letters Patent.

Patented April 20, 1909.

Application filed August 7, 1905. Serial No. 273,209.

To all whom it may concern:

Be it known that I, THOMAS AITKEN, a subject of the King of Great Britain, residing at Cupar-Fife, in Scotland, have invented certain new and useful Improvements in Methods of Forming Surfaces on Roads, of which the following is a specification.

This invention relates to improvements in the treatment of unpaved or macadamized roads with coal tar, crude oil or other surface-dressing liquids to prevent the formation of dust.

Hitherto it has been customary to sprinkle the more liquid dust-laying fluids from an ordinary watering cart or otherwise to apply the material under ordinary pressure.

According to this invention a surface-dressing liquid is discharged under considerable pressure from a distributing apparatus and is forced into the crust of the road.

Any suitable apparatus may be employed in carrying out my invention, as a horse-drawn or motor vehicle provided with a liquid supply tank, a receiver from which the liquid is distributed and a pump preferably automatically driven from a moving part of the vehicle and arranged to supply the liquid from the tank to the receiver under considerable pressure. An air valve and a regulating valve may be employed between the supply tank and the pump to control the contents of the receiver.

In the accompanying drawings, Figure 1 is a side elevation, and Fig. 2 an end elevation of one form of liquid-distributing vehicle which may be used.

Like letters indicate like parts in both figures.

Mounted on the frame A on the vehicle is a supply tank B to contain the surface-dressing liquid. A receiver C for liquid and air under pressure is placed at the back of the tank and is connected by an inlet pipe D with an air or liquid pump E. The pump is operated from a road wheel F by a chain wheel G fixed to the road wheel which drives through a chain H to a toothed pinion J actuating the crank shaft K of the pump E. The inlet L to the pump is connected with the supply tank B by a tube M which is conveniently a flexible metallic tube at the tank end, and a rose or strainer N is fixed on the end. An air inlet and regulating valve O is provided on the pipe M between the supply tank and the pump so that either air or

liquid may be admitted to the pump or the proportion of liquid and additional air may be regulated as required for the purpose of agitating and mixing the liquid properly.

Feed pipes P leading from the receiver C and provided with cocks Q conduct the liquid under pressure to a distributing pipe R having jets 'R' which discharge the liquid onto the road. The distance between the distributing pipe and the surface level of the road may, if desired, be variable to suit the varying pressures in the receiver, the condition of the road, etc. A pressure gage and safety valve T are provided on the receiver C.

Preferably air is forced into the receiver C from the pump E until the desired pressure of say, 50 to 100 pounds per square inch is established according to the viscosity of the liquid to be used and other conditions; the strainer N is then introduced into the tank, or connection otherwise made between the tank B and the pump, and liquid is forced into the receiver until the pressure reaches the required degree, say, from 150 to 250 pounds per square inch.

The apparatus is now ready for work and by opening the supply cocks Q to the distributor R, the liquid is squirted, preferably in the form of fine compact solid streams, of say, less than one-eighth of an inch in diameter so as to be of a penetrating character as they are forced directly onto the surface of the road and are also forced into the binding material forming a part of the crust of the metaled surface of the road. The liquid is pumped into the receiver C in a continuous flow and the compressed air originally introduced into the receiver maintains a uniform pressure.

The position of the tank, air-receiver and pump may be varied to suit the form of the vehicle on which the apparatus is to be employed. In the case of a motor vehicle the necessary power to drive the pump may be derived directly from the engine and a clutch may be used to put the pump into or out of gear.

As a result of the operations described the road material is penetrated by the oil or suitable composition forced downward in small solid streams at a high pressure, and thereby there is formed an upper or wearing layer of road material and oil combined, but without the usual preliminary mixing,

spreading and rolling. This layer therefore will become more solidified and cohesive under use than when the mixture is first made and spread and will unite better with the under layer or body portion, and the road is unusually permanent, durable and resistant to water. The cost of treatment is of course only a fraction of that required by ordinary methods.

10. Without limiting myself to the use of any special apparatus, or to any special liquid material or composition, I claim:

The within described mode of surfacing roads, consisting in forming a surface crust

by projecting a surface dressing liquid in 15 fine solid streams against the surface of the road bed, under such pressure exceeding fifty pounds per square inch as will cause the streams to penetrate the body of the road material.

20. In testimony whereof I have signed my name to this specification in the presence of two subscribing witnesses.

THOMAS AITKEN.
